By his attorney Geo. R. Seeler

UNITED STATES PATENT OFFICE.

ROLAND W. BROWN, OF NEW YORK, N. Y.

STATIC ELIMINATOR FOR RADIO EQUIPMENT.

Application filed January 17, 1928. Serial No. 247,278.

This invention relates to radio static filtering devices.

Among the objects of the invention is to provide a device for thoroughly eliminating static from radio receiving sets and similar apparatus which device may comprise a plurality of separate independent units inserted in the circuit of the receiving set at such points as may be most advantageous and 10 preferably, for example, in the lead extending to the antenna and also in the ground circuit.

Another object of this invention is the provision of a device of the character described wherein an improved preparation for filtering static from a radio receiving apparatus or the like comprises preferably a woody material, the latter being for highest efficiency of a finely divided form and having extended electrical surface contact with 20 an electrical conductor of a proper circuit.

A further object of the invention is to produce a device of the species mentioned wherein an electrical circuit associated with 25 a radio receiving set may include therein a finely divided material, such for example, as wood, which material is impregnated with an electrical conducting salt.

With the foregoing and other objects in 30 view the invention consists in the arrangement and combination of parts hereinafter described and claimed, and while the invention is not restricted to the exact details of construction disclosed or suggested herein, 35 still for the purpose of illustrating a practical embodiment thereof reference is had to the accompanying drawings in which like reference characters designate the same parts in the several views, and in which—

40 Figure 1 is a diagrammatic view in elevation of an embodiment of the invention.

Fig. 2 is a longitudinal cross section of an aerial filter embodying the invention.

Fig. 3 is a cross section taken on the line 45 3—3 of Fig. 2.

Fig. 4 is a longitudinal cross section with a part removed and showing an embodiment of the invention in the ground filter.

Fig. 5 is a cross sectional view taken on 50 the line 5—5 of Fig. 4.

Referring in detail to the drawings, 10 denotes a device embodying the invention, said device may include a radio receiving set 11, an antenna 12, and a ground 13.

55 The receiving set is connected at binding

posts 14 and 15 to the antenna and ground respectively by conductor wires 16 and 17. Interposed in the aerial and ground circuits are filters 18 and 19 respectively. These devices are of simple and compact construction and may be mounted in any convenient manner so as to be neat and inconspicuous. 60

The aerial filter 18 is mounted upon a bracket 18^a to which it is engaged in any suitable manner as, for example, by means 65 of straps 20. The latter preferably pass around an elongated tubular container 21. The said container 21 is preferably made of any insulating material such as paper, or the like. Coaxially mounted therein is an 70 inner tubular member 22, having its side wall spaced from the sides of the chamber 21, but extending substantially from end to end of the same. The inner member 22 is filled with a finely divided material 22^a, preferably 75 sawdust, which is impregnated with electrically conductive salt solution, as will be described hereinafter. The member 22 is formed with enlarged ends 23. An electric terminal 24 is inserted at one of said ends 80 and extends through an adjacent end wall of the chamber 21. In the other end of said container is placed a terminal 25 in the form of a stopper. The said terminals are in contact with the conductive static absorbing 85 material 22^a, which forms part of the electric circuit.

The said inner tube 22 is preferably made of soft or hard rubber, glass, wood, or the like, and in practical use is approximately 90 two feet long. As illustrative of the proportions of the material used in the inner tube, I offer the following: To four ounces of pure water, I add two tea spoonfuls of (heaped) Rochelle salts, and about one 95 spoonful of (heaped) table salt. When the above have been thoroughly mixed, I soak about ten spoonfuls of wood sawdust in the solution, and add a tea spoonful of glycerine to keep the solution from drying too soon. 100 The sawdust is then packed solidly into the inner filter tube.

From the terminal 25, a conductor 26 extends along the tube 22 to an external terminal 27. Preferably the said conductor 105 consists of a copper wire wound around the filter tube 22, with its coils in spaced relation. The said wire may be of No. 22 gage, uninsulated, and I may use 22 or 23 feet of it. About the said filter tube is packed dry 110

sawdust 28. Thus the wire coil has extended surface contact with the sawdust, the latter furnishing the final stage in filtering out static, interference, and noises.

5 It is thus seen that I have provided a filtering device for use in conjunction with the antenna of a radio receiving apparatus which includes an extended circuit having improved absorption features. The said circuit is seen to include a woody material as an essential part of it, and also various auxiliary features such, for example, as the electrically conductive solution used with the sawdust in the inner tube 22, and also the 10 outer coil conductor 26. In the device as shown current first flows in one direction through the material in the inner tube and then finally in a reverse direction through the coil extending along the same tube. In 15 this way the economy of space is effected and absorption of static is provided for in two separate stages, the second of which occurs in connection with the dry sawdust between the inner and outer tubes. The 20 filter 19 applied in the ground circuit includes a wooden core 30 of thin rod-like form extending coaxially through a tubular casing or chamber 31 in spaced relation to the side wall thereof and in proximity to the end walls of the chamber. Terminals 25 32 and 33 may be formed with integral screw threaded shanks 34 which extend into the end portions of the said core so as to mount the same within the casing. A coil 30 of conductive material 35 such, for example, as copper wire is wound around the said core and engages at its ends the said terminals. The said wire is preferably of No. 22 gage, uninsulated, and the coils thereof 35 are spaced uniformly along the inner core so that approximately 22 or 23 feet of the same are required. Packed around the said inner core and fully occupying the space between the latter and the outer casing 31 40 is a quantity of sawdust 36 used to take up the ground static. The casing 31 is preferably made of a non-conducting material as, for example, rubber, glass, or wood. The same operates in an efficient manner 45 jointly with the sawdust 36 to eliminate interference in radio receiving sets and all 50

those noises which detract from the quality of the music.

It is thus seen that I have provided a device which is simple in construction and 55 operation, inexpensive to manufacture, and practical and efficient to a high degree in use. By this invention the several objects herein set forth are fully achieved and the pleasure of the user of a radio set greatly 60 enhanced.

I claim:

1. A device of the character described, including an inner container of non-conducting material, a finely divided non-conducting material in said container, saturated with a salt, said salt being electrically conductive, an electrical terminal contacting said finely divided material, an electrical conductor extending along the exterior of 70 said container, an outer container surrounding the inner one, a non-conducting material in the outer container packed about the inner container and the conductor thereon, said conductor contacting at one end said 75 finely divided material remote from said terminal, and another terminal connected to the other end of said conductor.

2. A device as set forth in claim 1, wherein said finely divided material consists of sawdust.

3. A device of the character described, including an inner container of non-conducting material, a finely divided non-conducting material in said container, saturated with a salt, said salt being electrically conductive, an electrical terminal contacting said finely divided material, an electrical conductor extending along the exterior of 85 said container, an outer container surrounding the inner one, a non-conducting material in the outer container packed about the inner container and the conductor thereon, said conductor contacting at one end said 90 finely divided material remote from said terminal, and another terminal connected to the other end of said conductor, said finely divided material consisting of sawdust, and said non-conducting material in said outer container consisting of sawdust.

In testimony whereof I affix my signature.
ROLAND W. BROWN.
